UNITED STATES PATENT OFFICE.

CHARLES G. DOBBS, OF NEW YORK, N. Y.

REGISTER-FRONT.

SPECIFICATION forming part of Letters Patent No. 344,640, dated June 29, 1886.

Application filed February 15, 1886. Serial No. 191,963. (No model.)

To all whom it may concern:

Be it known that I, CHARLES G. DOBBS, of the city, county, and State of New York, have invented a new and useful Improvement in 5 Register-Fronts, of which the following is a specification.

My improvement consists of a register-front—by which I intend the front open-work plate of a hot-air register or radiator—having 10 sunken in it a recess or recesses of suitable shape and size to receive or support the feet of a person, the object being to furnish a register or radiator front formed in its open-work part with a support or receptacle for the feet.

15 In the accompanying drawings is represented a register-front embodying my improvement.

Figure 1 is a perspective view, and Fig. 2 is a transverse vertical section of the same.

20 The plate is of the usual or suitable contour and size, and is cast, as usual, with an open-work pattern of some kind to furnish the apertures for the passage of the heated air. This open-work part, as seen, starting from the

25 upper edge or border of the plate, slants rearwardly as it extends downward, so that at or

near the bottom it is far enough to the rear of the face of the plate to form a recess, the bordering flange of which constitutes a rest for the feet, and it is so shaped as to readily 30 receive and fit the heel of the shoe or foot. Such a construction as this (conveniently embodied in a single casting) is to be preferred when the front plate is of contracted dimensions. In larger plates, however—such as the 35 open-work plates of large registers or of radiators—the receiver may be sunken in such shape as to have the full contour of the foot or of a pair of feet.

Having described my improvement, what I 40 claim, and desire to secure by Letters Patent, is—

A register-front having sunken in its open-work portion a foot rest or recess, as and for the purposes hereinbefore set forth. 45

In testimony whereof I have hereunto set my hand.

CHARLES G. DOBBS.
